UNITED STATES PATENT OFFICE.

JACOB FELDGUS, OF CARBONDALE, PENNSYLVANIA.

GLOVE.

1,261,374.

Specification of Letters Patent.

Patented Apr. 2, 1918.

Application filed March 9, 1917. Serial No. 153,664.

To all whom it may concern:

Be it known that I, JACOB FELDGUS, a citizen of the United States, residing at Carbondale, in the county of Lackawanna and State of Pennsylvania, have invented certain new and useful Improvements in Gloves; and I do hereby declare the following to be a full, clear, and exact description of the invention, such as will enable others skilled in the art to which it appertains to make and use the same.

This invention relates to gloves, and has for its object to improve the construction of the pattern of the glove so as to facilitate the sewing of the parts together, and with the further object of economizing in the quantity of material which may be utilized in the manufacture of the glove by the peculiar design of a main pattern and two smaller patterns representing the backs of the second and third fingers, these parts being adapted to be sewed together in a manner to produce the desired formation of the fingers and to effect the location of the seams where they will be protected.

My present invention consists in a glove constructed of a main pattern portion having formed integrally therewith the front and back of the thumb, the front and back of the first finger, and the front and back of the fourth finger, and the fronts or palm portions of the second and third fingers, and further consists in the provision of two comparatively small sections forming the backs for the second and third fingers which are adapted to be sewed together prior to attachment to the main body portion of the glove.

In the following specification there is described one embodiment of my invention which is illustrated in the drawings wherein:

Figure 1 is a plan view of the main glove pattern or blank.

Fig. 2 is a plan view showing the two blanks for the backs of the second and third fingers.

Fig. 3 shows the back members of the second and third fingers as stitched prior to attachment to the glove.

Fig. 4 is a view of the back of the glove showing the position and method of securing the intermediate fingers to the main pattern of the glove, and

Fig. 5 is a perspective view of the complete glove looking toward the palm thereof.

In the form of the glove herein disclosed in Fig. 1 there is shown the pattern or blank

in plan view, this consisting of the palm portion P and the back portion B at the right and left hand sides respectively of the view, there being provided at the top portion of the pattern the front finger portion 1^a of the index finger, and similarly the front finger portions 2^a, 3^a and 4^a, these being disposed to appear at the inside or palm of the finished glove. Integrally formed along one side of the portion 4^a there is provided a back portion 4^b of suitable length to be folded over and stitched to the portion 4^a to form the little finger, while at the opposite side of the pattern there is provided a thumb portion 5^b forming the back of the thumb, and adjacent to this is the finger portion 1^b which is adapted to be stitched as hereinafter described to the portion 1^a to form the whole index finger. Below the front or palm portion 1^a of the index finger there is provided a lower extending portion 5^a forming the palm element of the thumb which is adapted to be folded upwardly along the line 6 into the dotted line position so that when the pattern is folded to bring the side line 10 over the side line 11 the inside portion 5^a of the thumb will be superposed upon the outside portion 5^b, and when these are properly stitched they form the complete thumb.

For the purpose of securing the complete middle or second and third fingers the pattern shown in Fig. 1 is cut away at 7 to form an oval-shaped aperture, the upper side of which is split outwardly along a line 8, the wing portion 8^a being adapted to be folded over the finger portion 1^b and the portion 8^c being adapted to be folded rearwardly over the portion 4^b back to the end portions of the oval recess or notch 7. The backs of the second and third fingers are shown in Fig. 2 as comprising blanks having upwardly projecting and curved end portions, the lower ends of each of these blanks being cut with a reentrant angular portion at one side as at 2^a and curved along the bottom portion at 2^a, and the angular portions 2^a of each of the finger blanks 2^b and 3^b are adapted to be stitched together along the lines a and b to produce the attached blank shown in Fig. 3, the upper portion of the angular edges 2^a of the blanks 2^b and 3^b forming an angular seam the upper portion of which provides a fullness so that these finger portions may be passed in between the fingers of the glove to provide the necessary fit and fullness.

Having stitched the blanks 2^b and 3^b together along the lines *a* and *b*, the lower curvilinear edges, as shown in Fig. 3, are stitched to the lower edge of the notch 7, as shown in Fig. 4, at the back of the glove, the outwardly extending curved edges of the bottom portion of the attached blanks 2^b and 3^b, Fig. 3, are then secured to the lower edges of the wing portions 8^a and 8^b, respectively, forming the complete finger blank for the rear side or back of the glove.

Having thus provided a blank, as in Fig. 1, of the proper size and shape and stitched the finger sections 2^b and 3^b, Fig. 2, together as in Fig. 3, and then having applied these latter to the curved edge of the notch 7, Fig. 1, the whole blank is adapted to be folded upon itself so as to bring the edge 10 into overlapping relation with the edge 11 below the back of the thumb 5^b, and the blank is then stitched in one continuous seam S starting from the lower or wrist portion of the glove and continuing along the superposed edges of the portions 10 and 11, the edge of the back portion 5^b of the thumb being stitched to the upwardly folded portion 5^f shown in dotted lines, and thence continuing around the edge of the index portion 1^b and 1^f where these are superposed, this stitch being continued entirely around the overlapping edges of the first, second, third and fourth fingers continuously until the whole edge of the glove has been stitched. It will be seen from this that the stitching of the edges of the super-

posed plies of the glove will terminate at the reentrant angle between the top ends of the portions 4^f and 4^b of the little finger.

It is obvious that a glove of this type may be constructed from any suitable material, such, for instance, as leather, cotton, wool or other fabric, and may be made rapidly in large quantities owing to the simplicity of the stitches, and may be made inexpensively by reason of the economy of material.

What I claim is:

A glove comprising an integral blank having palm and back portions provided with elements for all the fingers and thumb excepting the backs of the second and third fingers, and having an oval shaped opening between the bases of the first and fourth fingers, these latter being divided on a line outward from said opening, similar patterns for the backs of the second and third fingers stitched along reentrant angular portions of their edges to provide a cross-seam therebetween at the root of the fingers to the palm, said pattern stitched at its bottom edge to the edge of the said opening, and stitching connecting the edges of the folded back and palm and the superposed respective front and back finger and thumb elements.

In testimony whereof I affix my signature in presence of two witnesses.

JACOB FELDGUS.

Witnesses:

ROSE M. FARBER,
JOHN R. SHEPHERD.
